ROTARY HOOK FOR SEWING MACHINES

George Sauer, Berwyn, Ill., assignor to Union
Special Machine Company, Chicago, Ill., a cor-
poration of Illinois

Application September 7, 1933, Serial No. 688,512

13 Claims. (Cl. 112—256)

The invention relates to new and useful improvements in a rotary hook for a lock stitch sewing machine, and more particularly to the means for furnishing lubrication to the inter-
5 engaging parts between the rotary hook and the stationary bobbin casing.

An object of the invention is to provide a means for directing lubricant to the interengaging parts between the rotary hook and the bobbin casing
10 whereby lubrication is furnished said parts while the hook is rotating, and whereby the ports or channels supplying the lubricant to the operating parts may be readily rendered accessible for cleaning.

15 In the drawing, which shows by way of illustration one embodiment of the invention:

Figure 1 is a vertical sectional view through a rotary hook, the bobbin casing and the bobbin, and a portion of the actuating mechanism for the
20 hook.

Figure 2 is a perspective view of the rotary hook showing the plate covering the channels as separated from the hook in order to make clear the structure of the parts. The parts of the ro-
25 tary hook which cooperate therewith in completing the race for the bobbin case are removed in this view.

Figure 3 is a sectional view at right angles to one of the channels in the hook and showing the
30 cover plate therefor.

The invention has to do with a lubricating means for the interengaging parts between the rotary hook and the stationary bobbin casing. The rotary hook is fixed to the end of a rotating
35 shaft and the bobbin casing is mounted within and supported by the rotating hook. Said bobbin casing is provided with a circumferential rib which engages a groove or raceway in the rotary hook and thus prevents the bobbin casing from
40 lateral movement in the hook. Extending longitudinally of the shaft and centrally thereof is a port preferably provided with a wicking, and this port is open at the end of the shaft. The shaft extends into the rotary hook and terminates
45 short of the inner face of the hook so as to provide a recess on the inner face of the hook at its axis of rotation. The lubricating oil is fed into this recess from the port in the shaft. The sleeve in which the shaft rotates, as well as the shaft, has an opening leading to said central port, and means is provided whereby a lubricant may be supplied through these openings to the central port in the shaft and thus to the recess. On the
50 inner face of the rotating hook are a series of radial channels which extend all the way to the

recess in the hook which receives the rib on the bobbin casing, that is, the interengaging parts between the hook and bobbin casing. These channels are open on their inner face and are covered and closed by a removable plate which is
5 attached to the hook by screws. This plate extends throughout the greater portion of the length of the channels and serves as a ready means whereby access may be had to the channels for cleaning the same when the plate is removed.

Referring more in detail to the drawing, the invention is shown as applied to a sewing machine having a work support 1 provided with a suitable bearing bracket in which is mounted a 15 bushing 2, and in this bushing 2 is mounted a shaft 3 which carries the rotating hook 4. The shaft 3 is provided with a gear 5 meshing with a driving gear 6. These gears are enclosed in a chamber 7 which may be supplied with a lubricating oil so that the gears will run in oil. The specific form of mounting for the rotary hook forms no part of the present invention per se, but is shown, described and claimed in the application filed by Norman V. Christensen and Charles F. Rubel, May 9, 1933, Serial No. 670,186.

The rotary hook 4 is of the usual construction. It is cup-shaped with portions cut away forming spaced radial webs 8 which are formed as a part of a hub 9. This hub is slipped onto the end of 30 the shaft 3 and is secured thereto by set screws 10, 10. One side wall of the cup is cut away to provide a hook 11 which is adapted to enter the needle thread loop and carry the same about the bobbin casing containing the bobbin. On the inner face of the cup-shaped hook is a groove or raceway 12. The bottom wall and one side wall of the race only is shown in Fig. 2. The parts of the rotary hook which form the other wall of 35 the race are removed. These parts, however, are 40 of the usual construction.

Located within the rotating hook is a bobbin casing 13. Said bobbin casing is likewise cup-shaped and is adapted to receive a bobbin 14 which is mounted for free rotation within the bobbin casing. The bobbin is held within the bobbin casing by a cover or carrier 15. The bobbin casing is provided with a projecting portion 16 which is adapted to engage a member fixed to the frame of the sewing machine so that the bobbin casing is held stationary and does not rotate. The bobbin casing is provided with a circumferential projecting rib 17 which freely engages the raceway or groove 12 in the rotary hook. This bobbin casing is mounted in the hook 50

55

and is supported thereby. It is held from lateral movement through the interengaging parts consisting of the rib and the raceway. This rib fits loosely in the raceway and the needle thread loop is passed about the same in the usual manner. The means which prevents the bobbin from rotating is of such a character as to permit this loop to pass freely about the bobbin casing. These parts are of the usual construction and further description thereof is not thought necessary.

The present invention has particularly to do with a means for lubricating the interengaging parts between the bobbin casing and the rotary hook. When the hub 9 is placed on the shaft 3 and secured thereto, there is preferably left a space between the end of the shaft and the inner face of the rotating hook, thus forming a recess 18. This recess is open at the inner face of the rotating hook and is disposed at the axis of the rotating hook. Extending radially of each web 8 and centrally along the same is a channel 19. This channel 19 also extends along the inner face of the hook as indicated at 20 so that the channel leads all the way from the recess 18 to the raceway 12 in the rotating hook. There are three of these channels as illustrated in the present embodiment of the invention. This number, however, may be varied as desired, and in fact only one channel may be used instead of a plurality of channels. The channels are open at the inner face of the hook and are covered throughout a greater portion thereof by a plate 21. Said plate bears against the inner face of the hook and is located between the hook and the bobbin casing. The plate is secured to the hook by suitable screws 22 passing through openings 23 in the plate and threaded into the hook. This plate extends out along the channels, covering the same, and thus forming substantially closed ports leading from the recess 18 to the channels at the periphery of the hook. This plate covers the recess 18 and the channels 19, and when the plate is removed, the recess and channels are exposed and rendered accessible for cleaning.

The shaft 3 is provided with a central bore 24 which extends all the way to the end of the shaft and thus connects with the recess 18. There is a radial port 25 extending through the shaft to the port 24 therein. The bushing 2 is provided with an opening 26 which may be brought into register with the opening 25. The work plate is provided with an opening 27 which is in register with the opening 26. A wicking 28 is preferably placed in the bore 24 of the shaft. Lubricating oil fed through the opening 27 to the bore 24 in the shaft will be fed into the recess 18. Said recess becomes a distributing chamber for supplying oil to the channels 19. The oil is caused by centrifugal force, to pass out along the channels 19 to the race, thus furnishing lubrication for the interengaging parts between the bobbin casing and the rotary hook. By removing the bobbin casing from the hook, this plate 21 may be very easily removed and thus the channels uncovered, as well as the recess 18, for the purpose of freeing the same from any accumulating obstruction therein.

It is obvious that minor changes in the details of construction can be made without departing from the spirit of the invention as set forth in the appended claims. Moreover, the reference herein to the means employed for covering the lubricant channel in the rotary hook as a "plate" is to be construed broadly and is intended to com-

prehend any equivalent device affording a wall for closing the side of the lubricant channel.

Having thus described the invention, what I claim as new and desire to secure by Letters Patent, is:

1. In a sewing machine, the combination of a rotary hook, a stationary bobbin casing supported therein, said hook and casing having interengaging parts preventing lateral movement of the casing in said hook, said hook having on its inner face a radial channel extending substantially from the axis thereof to said interengaging parts for directing lubricating oil to said parts, a plate removably secured to the inner face of said rotating hook and covering said channel throughout the greater portion of its length, and means whereby lubricating oil may be supplied to said channel at the axis of the hook.

2. In a sewing machine, the combination of a rotary hook, a stationary bobbin casing supported therein, said hook and casing having interengaging parts preventing lateral movement of the casing in said hook, said hook having a recess on its inner face at the axis of rotation thereof and a radial channel extending from said recess to said interengaging parts for directing lubricating oil to said parts, a plate removably secured to the inner face of said rotating hook and covering said recess and said channel throughout the greater portion of the length of the channel, and means whereby lubricating oil may be supplied to said recess.

3. In a sewing machine, the combination of a rotary hook, a stationary bobbin casing supported therein, said hook and casing having interengaging parts preventing lateral movement of the casing in said hook, a shaft on which said hook is mounted, said shaft having a port centrally thereof, a recess in said hook at the end of the shaft with which said port connects, radial channels extending from said recess to said interengaging parts for directing lubricating oil to said parts, a plate removably secured to the inner face of said hook and covering said recess and said channels throughout the greater portion of the length of the channels, and means whereby lubricating oil may be supplied to said port in said shaft.

4. In a sewing machine, the combination of a rotary hook having a raceway formed therein, a stationary bobbin holding means journaled in said raceway, and means for supplying lubricating oil to said raceway at a plurality of points by centrifugal force, said last-named means including at least one radially disposed duct leading from a point near the axis of said hook to a point adjacent said raceway, said duct comprising a channel and a removable cover plate therefor which renders said channel readily accessible for cleaning.

5. In a sewing machine, the combination of a rotary hook, a stationary bobbin casing supported therein, said hook and casing having interengaging parts preventing lateral movement of the casing in said hook, a plate removably secured to the inner face of said rotating hook and extending outwardly to the rim portion of the hook, said hook and plate having therebetween a series of radially extending ports for directing oil outwardly to said interengaging parts.

6. In a sewing machine, the combination of a rotary hook, a stationary bobbin casing supported therein, said hook and casing having interengaging parts preventing lateral movement of the casing in said hook, said hook having a rim portion, a hub and spaced radial webs ex-

tending from the hub portion to the rim portion, means removably secured to the inner face of said radial web portions and forming therewith a radial channel extending from the hub portion 5 of the hook to the rim portion for directing oil from a source of supply at the hub to the interengaging parts.

7. In a sewing machine, the combination of a rotary hook, a stationary bobbin casing supported therein, said hook and casing having interengaging parts preventing lateral movement of the casing in said hook, said hook having a rim portion, a hub and spaced radial webs extending from the hub portion to the rim portion, means 10 removably secured to the inner face of said radial web portions and forming with at least one of said webs a radial channel extending from the hub portion of the hook to the rim portion for directing oil from a source of supply at the hub 15 to the interengaging parts, said rim portion having a channel in alignment with the channel in a web portion and leading to the interengaging parts.

8. In a sewing machine, the combination of a rotary hook, a stationary bobbin casing supported in a raceway formed in said hook and restrained against lateral movement relative to said hook by the sides of said raceway, said rotary hook comprising a hub and a rim portion 30 connected by a plurality of spaced radial webs, an oil channel formed in the inner face of one of said webs and extending from the hub to the rim portion and a plate secured to said hook and covering said channel in the web thereof.

35 9. In a sewing machine, the combination of a rotary hook, a stationary bobbin casing supported in a raceway formed in said hook and restrained against lateral movement relative to said hook by the sides of said raceway, said rotary hook comprising a hub and a rim portion connected by a plurality of spaced radial webs, an oil channel having communicating portions formed on the inner face of one of said webs and on the inner face of said rim portion and extending from said 40 hub to said raceway, and a plate secured to said hook and covering said channel in the web thereof.

10. In a sewing machine, the combination of a

rotary hook, a stationary bobbin casing supported in a raceway formed in said hook and restrained against lateral movement relative to said hook by the sides of said raceway, said rotary hook comprising a hub and a rim portion connected by a 5 plurality of spaced radial webs, an oil channel formed in the inner face of each radial web and extending from the hub to the inside of said rim portion, and a removable plate secured to said hub portion and covering said channels. 10

11. In a sewing machine, the combination of a rotary hook, a stationary bobbin casing supported therein, said hook and casing having interengaging parts preventing lateral movement of the casing in said hook, a shaft on which said hook 15 is mounted, said shaft having an oil conveying port centrally thereof, and said hook having an axially bored hub portion engaging the shaft and forming a recess at the end of the shaft connected with said port, said hook having on the inner face 20 thereof radial channels extending from the recess to said interengaging parts for directing lubricating oil to said parts, means removably secured to the inner face of said hook for covering the recess at the hub of the hook and the channels 25 leading therefrom throughout a greater portion thereof, and means whereby lubricating oil may be supplied to said port in said shaft.

12. In a sewing machine, the combination of a rotary hook, a stationary bobbin casing supported 30 therein, said hook and casing having interengaging parts preventing lateral movement of the casing in said hook, a member rigidly secured to said hook and forming therebetween at a face of the hook a series of radially extending channels for 35 directing oil outwardly from the hub of the hook to the interengaging parts.

13. In a sewing machine, the combination of a rotary hook, a stationary bobbin casing supported therein, said hook and casing having interengag- 40 ing parts preventing lateral movement of the casing in said hook, and means removably attached to the inner face of the hook and forming therewith a series of radially extending channels for 45 directing oil outwardly from the hub of the hook to the interengaging parts.

GEORGE SAUER.
